(57) **CLAIM**

The ornamental design for a paired set of a personal audio output device with surface ornamentation, as shown and described.

DESCRIPTION

FIG. 1 is a side view of the right one of a paired set of a personal audio output device with surface ornamentation showing my new design, shown separately for ease of illustration;

FIG. 2 is a front isometric view of the personal audio output device of FIG. 1;

FIG. 3 is a back view of the personal audio output device of FIG. 1, showing a back façade of the personal audio output device;

FIG. 4 is a back isometric view of FIG. 3;

FIG. 5 is a front end view of the personal audio output device of FIG. 1;

FIG. 6 is a back end view of the personal audio output device of FIG. 1;

FIG. 7 is top view of the personal audio output device of FIG. 1;

FIG. 8 is a bottom view of the personal audio output device of FIG. 1;

FIG. 9 is a side view of a left one of a paired set of a personal audio output device with surface ornamentation showing my new design, shown separately for ease of illustration;

FIG. 10 is a front isometric view of the personal audio output device of FIG. 9;

FIG. 11 is a back view of the personal audio output device of FIG. 9, showing a back façade of the personal audio output device;

FIG. 12 is a back isometric view of FIG. 11;

FIG. 13 is a front end view of the personal audio output device of FIG. 9;

FIG. 14 is a back end view of the personal audio output device of FIG. 9;

FIG. 15 is top view of the personal audio output device of FIG. 9;

FIG. 16 is a bottom view of the personal audio output device of FIG. 9;

FIG. 17 is a front view of a paired set of a personal audio output device with surface ornamentation showing our new design; and,

FIG. 18 is a front view of a paired set of a personal audio output device of the left and right ear.

The broken-line showing of the personal audio output device in all the figures is for illustrative purposes only and forms no part of the claimed embodiments.

The stippled surface shading discloses shading, tone and surface texture.
